United States Patent Office

Des. 229,163
Patented Nov. 13, 1973

229,163

DOOR CHAIN LOCK

Louis G. Bobrowski, Berlin, Conn., assignor to The Stanley Works, New Britain, Conn.

Filed Mar. 7, 1972, Ser. No. 232,654

Term of patent 14 years

Int. Cl. D8—07, 09

U.S. Cl. D8—131

FIG. 1

FIG. 2

FIG. 3

FIG. 1 is a perspective view looking upwardly towards the front of a door chain lock showing my design;

FIG. 2 is a perspective view looking downwardly towards the rear of the door chain lock shown in FIG. 1; and

FIG. 3 is a front elevational view of a lock housing of the door chain lock shown in FIG. 1.

The chain has been shown broken away in FIG. 3 for convenience of illustration.

I claim:

The ornamental design for a door chain lock, as shown.
